AUTOMATIC SWITCH CONTROL MEANS
FOR KILNS

Wilfred P. Dawson, Detroit, Mich.

Application August 8, 1952, Serial No. 303,346

5 Claims. (Cl. 25—132)

1

In small kilns such as may be used by artists or by persons in pursuit of a hobby, the time required for satisfactory firing of objects within a kiln is ordinarily ascertained by visual observation of what is known as a pyrometric pile or cone. The cone, located within the kiln, has to be watched in the course of the firing through a transparent pane within the wall of the kiln, and when the cone is sufficiently softened by the heat within the kiln so that its top turns downwardly upon itself in a hairpin turn, it is an indication that the firing is complete, whereupon the heat applied to the kiln is cut off manually.

It was in order to eliminate the necessity of this observation of the cone and to eliminate the danger of having the heat turned off either too early or too late that I have devised my improvement. The improvement makes it possible to have the heat turned off at the right time, especially since the means employed by me call for the use of a pyrometric cone which except for the necessity of watching it, as mentioned above, has proved itself satisfactory and reliable.

I shall now describe my improvement with reference to the accompanying drawing in which:

Fig. 1 is a perspective view of my device with parts broken off in order that the details of the construction may be better disclosed;

Fig. 2 is a longitudinal sectional view of my device, the view including parts shown in a side elevation;

Fig. 3 discloses elements included in Fig. 2 but shows some of them in different operative positions;

Fig. 4 is a front elevational view of elements of my device as they are placed within the kiln;

Fig. 5 shows the same view but with parts in different operative positions.

Similar numerals refer to similar parts throughout the several views.

The assembled device is best shown in Fig. 1, disclosing parts located on the outside of the kiln to which it is applied, parts within the kiln, and intermediate elements positioned within an aperture in the wall of said kiln. All said parts and elements are preferably made of metal.

Located on the outside in abutment with the wall of the kiln is a vertical plate 10 supporting a box 11 which houses an electric switch of a standard design, by means of which switch electric current may be cut off by a pivoted arm actuated from outside. As no novelty is claimed in the structure of the switch, no further description thereof seems to be necessary beyond what may be said in the course of this specification.

2

Hinged to the front wall or plate 12 of the box by means of pillow blocks 13 and pintels 14 journalled therein is an arm 15 normally extending vertically from said pillow blocks, the arm 5 being provided at its lower end with an outwardly-projecting spur 16. Directly below the lower end of said arm 15 the front wall 12 of the box 11 is provided with an aperture 17 displaying a plate 18 within the box, to which plate reference 10 will be had hereinbelow.

The top of arm 15 is of a solid, heavy construction to cause said arm, unless detained in its upwardly-extending position, to swing downwardly by gravity. The top 19 includes two vertical flanges 20 disposed in a spaced, parallel relation to each other. A sliding plate 21 fitting into the space between said flanges is cut off horizontally at the top, as shown at 22, and is provided at the bottom with an outwardly-extending 20 lip 23 for manual operation thereof.

A vertical slot 24 within said plate 21 permits application of a screw 25 which passes through said slot to be threaded into the body of the top 19 of said arm 15. A washer 26 seated on the 25 shaft of the screw and abutting plate 21 from outside serves to retain on the screw one end of a coiled spring 27, while the opposite end thereof is kept in place by the head of said screw. Numeral 28 shows a screw designed to limit the 30 downward movement of the sliding plate 21.

At the top, above said box 11, plate 10 contains a circular aperture 29. Fitting into said aperture is a tube 30 threaded on the outside. A part of the tube projects through said aperture 29 outwardly, that is, in the direction of the switch box. Threaded upon said part is a nut 31, the nut being plugged at its outer end by a disc 32 which contains an axially-located opening 33.

Loosely fitting into said opening is a neck portion 34 of a cylindrical block 35 having an axial bore 36. The block serves as a means of supporting a standard shaft 37 which passes through said bore 36 and may be secured therewith against displacement by a set screw 38. One end of the 45 shaft extending in the direction of arm 15 supports a sliding member 39 having a disc-like flange 40. The flange bears from outside against the top of sliding plate 21. Numeral 41 indicates a set screw within said member 39.

Referring again to the above-said tube 30, it will be noted that it is disposed axially within a sleeve 42, the sleeve being threaded inwardly, as shown at 43, permitting a co-operative engagement with said tube 30. The sleeve carries at its outer end what may be designated as a clamp-

ing plate 44. The relative positions of plate 10 and said clamping plate 44 with respect to the wall 45 of the kiln is shown in Fig. 2, the wall being provided with a circular hole 46 transversely to the thickness thereof. The inner threading of said sleeve 42 and the outer threading of tube 30 permits said plates 44 and 10 to be spaced from each other to correspond to the thickness of the wall 45 of the respective kiln.

The outer end of the sleeve which is press-fitted into an opening 46 in a clamping plate 44 is closed by a plate 47 the marginal portions of which are secured to the outer face of plate 44. A vertical gate 48 within said plate 47 is wide enough to permit rod 37 to pass through it, as shown in the drawings. Welded to the outer face of plate 44 are two brackets 49, each of the brackets including a horizontal strip 50, the strips being disposed at the same level but being spaced from each other and straddling said gate 48.

Seated upon rod 37 at the end projecting through said gate and adjoining plate 47 is a disc-like weight 51. A set screw 52 penetrates the disc radially for a frictional engagement with the rod and serves to hold the disc against displacement.

To complete the description of my device I wish to add that the pyrometric cone or pile used in conjunction with my device is marked 53. It must be stated here that pyrometric cones come in a number of varieties to fit specific conditions and requirements as to their initial plasticity in response to a definite degree of temperature, as obviously items of slender structure or one kind of clay may require less heat or a lesser period of exposure to heat than items of heavier structure and of a different substance.

I shall now describe the manner in which my device may be used. First, a cone of a suitable variety is selected for the specific task, the cone being of the same variety which has been used in the kiln for visible observation of its contents, as already described in this specification. The cone is placed lengthwise upon two horizontal strips 50. For the first firing of the objects in the kiln equipped with my device it is advisable to place the base of the cone flush with the lateral edge of one of the strips. Next, rod 37 is allowed to drop crosswise upon the cone, in which position it will be held by weight 51. Assuming that arm 15 is in its normal upright position, the sliding plate 21 is shifted upwardly against rod 37 until the upper edge 22 of said plate will bear firmly against said rod, pressing the opposite end of the rod against the top of the pyrometric cone. To prevent the plate from sliding down, screw 25 is tightened against the outer surface thereof. While the rod is in this position the flange of the sliding member 39 which is seated on the rod will bear from outside against the top of said sliding plate 21.

Assuming now that the firing of objects within the kiln has been started and that the required temperature within the kiln has been kept for a sufficient time to soften the cone, rod 37, weighed by disk 51, will cause the cone to sag midway its length, as shown in Fig. 5. As with the sagging cone, the end of rod 37 resting thereon will sink below its original level shown in Fig. 4 to the level shown in Figs. 3 and 5, the opposite end of the rod will swing upwardly, as shown in Fig. 3, lifting member 39 out of contact with plate 22 mounted on arm 15.

Unchecked by flange 40 on said member 39,

arm 15 will swing away from its hinged lower portion from plate 12, causing spur 16 to enter aperture 17 and to depress the movable plate 18, thereby opening the switch. As a result thereof electric current supplied to the source of heat for the kiln will be cut off.

If it should appear that the pyrometric cone used in conjunction with my device has softened too soon as measured by the pyrometric cone placed within the kiln for visual control, the next cone used in my device may be shifted lengthwise so as to wedge up rod 37 from below by said cone at a point where its thickness is somewhat smaller than on the first trial. The longitudinal shift of the cone may be gauged with respect to one edge of the horizontal strip 50 which supports the thicker end of the cone.

Reversely, if the firing lasted beyond the period actually needed, the cone may be shifted in the opposite direction, exposing a thicker portion for contact with the rod.

While in the description of my device I have referred to electric means of heating the kiln, it will be obvious that the switch forming a part 25 of my device may control other means of supplying heat, such as gas. In such a case the switch would control electric current employed to operate a valve which supplies gas to a burner.

It will be understood that some changes may 30 be made in the construction of my device without departing from the inventive principle disclosed herein.

What I, therefore, wish to claim is as follows:

1. In combination with a kiln having a trans- 35 verse aperture in its wall, two plates adapted to clamp said wall therebetween, a tube disposed in said aperture and joining the two plates, an electric switch mounted on the outside plate and including an arm disposed normally in a vertical position but hinged at its lower end and weighted at the top to cause it to swing down unless restrained, bracket means mounted on the inside plate and including two horizontal strips laterally spaced from each other at a level below one end of the tube but parallel thereto, the strips being adapted to support a pyrometric cone in a substantially horizontal position, a rod within the tube, pivoted within the tube at its end adjoining the outside plate, a disc-like member supported by the rod, the member being adapted to engage the upper end of said arm to prevent its swing downwardly but to release said arm on the swing of the adjacent end of the rod upwardly, the opposed end of the rod being 45 adapted to rest on the pyrometric cone midway of its length and above the spacing between said horizontal strips, weight means on the part of the rod adjoining the inside plate to cause the rod to bear against the upper surface of said cone and to swing below the level of said upper surface with the sagging of the pyrometric cone on exposure to heat.

2. In combination with a kiln having a trans- 65 verse aperture in its wall, tubular means within said aperture, the tubular means being adjustable longitudinally, two horizontal strips mounted on the inside of said wall below the level of the aperture, the strips being horizontally spaced from each other and extending inwardly into the kiln, an electric switch outside the kiln, the switch including a hinged arm normally disposed in an inoperative position but tending by gravity to swing into an operative position, a rod disposed within said tubular means but projecting therefrom at each end thereof, the rod being

pivottally mounted therewithin, one end of said rod being weighted to bear from above upon a pyrometric cone supported on said horizontal strips at a point midway of said strips, the other end of the rod including means in a sliding contact with the arm to hold it in its inoperatiye position, the rod being adapted to swing down at the weighted end in response to the sagging of the cone by exposure to heat and at its other end to release the arm into its operative position to cut off means supplying heat to the kiln.

3. A device to actuate a switch controlling electric current for means to supply heat to a kiln, which kiln is provided with a transverse aperture in its wall, said device including two horizontal strips horizontally spaced from each other and mounted inside the kiln on the wall thereof, the strips being adapted to support a pyrometric cone in a substantially horizontal position, a switch outside the kiln but associated therewith, the switch including a hinged arm adapted to swing by weight into an operative position, a rod disposed within said aperture and pivoted at a point between its ends, one end of the rod being weighted down to bear from above against a pyrometric cone resting horizontally on the two strips and spanning the space therebetween, the other end of the rod including flange means for engagement with the arm to hold it in its inoperative position, the means being adapted to release the arm when the weighted end of the rod has swung to a level below the initial position of the rod on the cone as a result of the softening of the cone by exposure to heat, causing the other end of the rod to disengage said arm.

4. In combination with a kiln having a transverse aperture in its wall, a device to actuate a switch in an electric circuit controlling heat-supplying means for said kiln, the device including two horizontal strips secured to the wall of the kiln on the inside thereof, the strips being horizontally spaced from each other at the same level and being adapted to support the opposite ends of a pyrometric cone in a substantially horizontal position, an electric switch outside the kiln but associated therewith, the switch including a

- hinged arm adapted to be swung into an operative circuit-opening position, a rod extending from outside through said aperture and pivoted intermediate its ends, one of the ends being weighted to bear from above against the midportion of the cone and to sink lower therewith with the sagging body of the cone in response to the exposure of said cone to heat, the other end of the rod serving to normally keep the arm in its inoperative position but being adapted to release said arm into its operative position on being swung up by the lowering of the weighted end of said rod.
5. In combination with a kiln having an aperture in its wall, a device to actuate a switch in an electric circuit controlling heat-supplying means for said kiln, the device including two horizontal strips secured to the wall of the kiln on the inside thereof, the strips being spaced from each other at the same level, a pyrometric cone resting on said strips crosswise thereof and being adapted to be adjustably shifted lengthwise upon said strips, an electric switch outside the kiln but associated therewith, the switch including a hinged arm adapted to be swung into an operative circuit-opening position, a rod extending from outside through said aperture and pivoted to said wall intermediate its ends, one of the ends being weighted to bear from above against the portion of the body of the cone directly above the space between said strips, the other end of the rod being adapted by intermediate means to operate the switch.
